(57) **CLAIM**

The ornamental design for a disc pet chew, as shown and described.

DESCRIPTION

FIG. 1 is a front, top and right side perspective view of a disc pet chew according to the new design; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof; and, FIG. 8 is a bottom, front and right side perspective view thereof.

The evenly-spaced broken lines in FIGS. 1-8 illustrate portions of the disc pet chew that form no part of the claimed design. The dash-dot-dash broken lines in FIGS. 1, 3, 4 and 6-8 illustrate the boundary of the claimed design which forms no part thereof.

1 Claim, 5 Drawing Sheets
